(57) **CLAIM**

The ornamental design for a point of sale terminal, as shown and described.

DESCRIPTION

FIG. 1 is a perspective view of a point of sale terminal showing our new design.

FIG. 2 is a second perspective view thereof;

FIG. 3 is a bottom plan view thereof;

FIG. 4 is a right side elevational view thereof, the left side elevational view being a mirror image thereof;

FIG. 5 is a front elevational view thereof;

FIG. 6 is a back elevational view thereof; and,

FIG. 7 is a top plan view thereof.

The broken lines in the drawings are for illustrative purposes only and form no part of the claimed design.
